FRIEDRICH WILHELM OTTO LISTING, OF MILWAUKEE, WISCONSIN

COMPOSITION COFFIN

Application filed November 7, 1927. Serial No. 231,604.

This invention relates to improvements in composition coffins.

It is one of the objects of the present invention to provide a composition casket of attractive design and decoration which may be made and sold very much more cheaply than the caskets or coffins now on the market.

A further object of the invention is to provide a composition coffin which is practically indestructible and which will not decompose, and will protect and seal a corpse placed therein.

A further object of the invention is to provide a composition coffin in which the corpse is sealed in a solidified composition, with the result that it will become mummified.

A further object of the invention is to provide a composition coffin which is very simple and inexpensive, and is well adapted for the purposes set forth.

With the above and other objects in view, the invention consists of the improved composition coffin, and its parts and combinations as set forth in the claims, and all equivalents thereof.

In the accompanying drawing in which the same reference characters indicate the same parts in all of the views:

Fig. 1 is a plan view of the base of the improved coffin, with a corpse in place prior to the same being sealed and covered with a mortarized material;

Fig. 2 is a longitudinal sectional view of the completed composition coffin showing a corpse therein; Fig. 3 is a plan view thereof; and

Fig. 4 is a cross-sectional view taken on line 4—4 of Fig. 2, with the corpse omitted.

Referring now more particularly to the drawing, it will appear that the numeral 8 indicates a wooden base member formed of a pair of spaced longitudinally extending rails 9 joined by transverse slats 10 forming a bottom. Mounted on the upper surfaces of the slats are a pair of longitudinally extending side members 11 which are secured at their end portions to upstanding end members 12 secured between the end portions of the rails 9. The projecting end portions 9' of the rails are formed as handles and also

side handles 13 project laterally from the rails. The structure just described forms the base or skeleton of the improved composition coffin.

Prior to the use of the coffin, the bottom is made solid and air tight by having a mortar-like material or composition packed against the outer surface of the slats 10 between the rails 9 and outwardly of the rails 9, as indicated at 14 and 15. The composition is applied in a plastic state and is allowed to dry and harden, becoming very hard and practically unbreakable. Within the scope of the invention any mortar-like or cementitious material may be used, but it has been found very desirable to compound a substance using the following ingredients in the stated proportions: forty-five (45) parts of magnesite; twenty-eight (28) parts of hickory wood flour; five (5) parts of asbestos; and twenty-two (22) parts of white quartz silica. The above mixture has added thereto sufficient magnesium chloride to result in an earth wet, plastic mixture, and coloring matter, as experience dictates, may be added to secure effective coloring designs.

When a corpse is to be interred or mummified in the improved coffin, according to the invention, the corpse, indicated by the numeral 16, is placed on the bottom portion of the base, the bottom previously having been covered with a layer of velvet 17 or other fabric, to enhance its appearance. Then, as shown in Figs. 1 and 2, the body of the corpse is enclosed by a jacket 18, formed of cardboard, or other light and comparatively strong inexpensive material, and the side edges of the jacket are tacked to the base slats 10, as at 19. A small jacket 20, of similar material, is also provided for the head of the corpse and it is secured thereover, as shown. The top of the head jacket 20 is provided with a large window so that the face and features of the corpse will not be hidden, and said window is covered by a glass plate 22 resting on the jacket 20.

After the corpse has been thus jacketed on the base, it is entirely covered and sealed by a substantial layer of composition, indicated at 23, composed and applied as previously de-

scribed, built downwardly and outwardly evenly so as to effectively seal the interior space occupied by the corpse. The composition material is susceptible of being worked in colors and designs, so that the finished composition coffin will be very attractive.

A circular opening (see Figs. 2 and 3) is left in the composition layer 23 over the window so that until burial, the face of the corpse 10 will be visible. After the services and just prior to burial, the opening may be closed up with the same composition material.

It will thus be seen that the invention provides a unique manner of preparing a corpse 15 for interment and that the corpse is so sealed that it will be air-tight and will be preserved for a long period. Also, the coffin, being formed of an outside layer of solidified cementitious material, will be very strong and 20 hard and will withstand the ravages of the elements and time. Also, the improved composition coffin is simple, practical and novel.

What I claim as my invention is:

1. A coffin, comprising a flat base member 25 including spaced slats with cementitious material cast therebetween and on all sides of the slats, an arched form member mounted on the base member and having a glazed window therein, and an outer cementitious member of 30 inverted U-shape in cross-section molded at its edge portions to the base member and having an opening registering with said glazed window.

2. A coffin, comprising an elongated base member including a molded composition, a 35 molded, arched composition cover member sealed at its edge portions to the base member, and a form member interposed between the base and cover members and spacing the 40 same and differing in material from both of the same, said composition in the base and cover members being composed of suitable proportions of magnesite, hickory wood flour, asbestos, white quartz silica and magnesium 45 chloride.

In testimony whereof, I affix my signature.
FRIEDRICH WILHELM OTTO LISTING.
